UNITED STATES PATENT OFFICE.

CHARLES F. CLAYTON, OF BALKAN, KENTUCKY.

DRAWBAR FOR MINE CARS.

Application filed June 10, 1925. Serial No. 36,201.

To all whom it may concern:

Be it known that I, CHARLES F. CLAYTON, a citizen of the United States, residing at Balkan, in the county of Bell and State of Kentucky, have invented certain new and useful Improvements in Drawbars for Mine Cars, of which the following is a specification.

My said invention relates to a drawbar construction for mine cars of the type which are run into a rotary dump for emptying the car. In a dumping device of the above type in which a car goes into a cage and the cage is rotated to invert the car the car is often wrecked as the drawbars and shackles are twisted and often broken thereby rendering cars useless and involving great time and expense in the operation of unloading a mine car.

It is an object of the invention to provide a drawbar of simple construction and inexpensive to manufacture, which will permit a car upon which it is applied to be freely rotated to dump the same when coupled with other cars forming a train.

Referring to the accompanying drawings which are made a part hereof and on which similar reference characters indicate similar parts,

Figure 1 is a side elevation of my device, Figure 2, a bottom plan view,

Figure 3, an end elevation,

Figure 4, a perspective of one of the end boxings or bearings, and

Figure 5, a perspective of the coupling.

As shown in the drawings the invention comprises a car body 10 having a floor 11 supported by wheels 12 on axles 13 mounted in journal boxes or bearings 14. The car body is also preferably provided with a swinging end gate 15. Housing elements or boxings 16 are provided, one at each end of the car body in the center thereof supported between body braces or reinforcing elements 17 and 18 above and below the floor 11 of the car. The braces 17 extend upward and conform to the body of the car and reinforce the same while the braces 18 extend merely transversely beneath the floor. Bolts 19 extending through the floor clamp the braces 17 and 18 together.

A drawbar 20 is supported in the boxings or housings 16, said drawbar being formed of a continuous rod or bar and having an opening in its end for reception of a cou-

pling member. Also I preferably provide the drawbar with a collar 21 adapted to bear against the outer end of the housing 16. The housing or boxing 16 is preferably formed of upper and lower sections adapted to be secured together by bolts so that they may be easily removed if such is desirable. The inner ends of the housings are provided with recesses 22 in which is mounted a casing 23 for the drawbar. This casing is of strong construction and maintains the housing elements 16 in proper spaced relation. From the foregoing it will be seen that the car body is free to rotate about the drawbar as an axis and force applied to the drawbar at one end of the car will be equally distributed between both of the boxings 16. The casing 23 is clamped directly between the centrally arranged body braces 17 and 18 and the supporting elements 16 for said casing are also secured in a similar manner.

Couplings are provided consisting of an odd number of links, preferably one or three, with a clevis at each end thereof. As shown in Figure 5 my coupling consists of links 23', each end link being provided with a clevis 24 having a pin 25 with an enlarged end to prevent the same from being removed, said pin being adapted to pass through the end of the draw bar.

The car floor 11 is preferably extended beyond the end of the drawbar at each side thereof to serve as bumpers and I preferably provide said extended portions with protecting and reinforcing plates 26.

In the above construction a string of cars while coupled may pass through rotary dumping devices and the cars may be overturned to remove the contents thereof without uncoupling them from the train and without damage to any part of a car.

It will be obvious to those skilled in the art that various changes may be made in my device without departing from the spirit of the invention and therefore I do not limit myself to what is shown in the drawings and described in the specification but only as indicated in the appended claims.

Having thus fully described my said invention, what I claim as new and desire to secure by Letters Patent, is:

1. The combination in a mine car, of a floor, braces extending across said floor on opposite sides thereof in opposed relation, housing elements secured between spaced

pairs of braces, and a drawbar extending the length of said body through said housing elements, substantially as set forth.

2. The combination in a mine car, of a floor, braces extending across said floor on opposite sides thereof in opposed relation, housing elements secured between spaced pairs of braces, a casing having one end nested in each of said spaced housing elements and serving as a reinforcement to maintain them in spaced relation, and a drawbar extending the length of said body through said housing elements and casing and having a stop adjacent the outer side 10 of said housing for preventing the longitudinal movement of said drawbar through said casing, substantially as set forth.

3. The combination in a mine car, of a body, a floor for said body, a brace adjacent each end of said body extending across said floor, a second brace at each end of said body secured on the opposite side of the floor, securing elements extending through said floor and connecting each pair of braces, a housing secured between each pair of braces intermediate their ends, and a drawbar mounted in said housings and extending throughout the length of the car, substantially as set forth.

4. The combination in a mine car, of a body, a floor for said body, a brace adjacent each end of said body extending across said floor, a second brace at each end of said body secured on the opposite side 35 of the floor, securing elements extending through said floor and connecting each pair of braces, a housing secured between each pair of braces intermediate their ends, a drawbar mounted in said housings and extending throughout the length of the car, and a casing for said drawbar supported by said housings between the same, substantially as set forth.

5. The combination in a mine car, of a body, a floor for said body, a brace adjacent each end of said body extending across said floor, a second brace at each end 45 of said body secured on the opposite side

of the floor, securing elements extending through said floor and connecting each pair 50 of braces, a housing secured between each pair of braces intermediate their ends, a drawbar mounted in said housings and extending throughout the length of the car, and a casing for said drawbar supported by 55 said housings between the same and assisting in holding said housings in spaced relation said drawbar having a stop adjacent the outer side of each housing for preventing the movement of said drawbar through 60 said housings, substantially as set forth.

6. The combination in a mine car, of a floor, a housing adjacent each end of said floor and having flanges on its top and bottom forming a channel between the same, a 65 casing having one end nested in each of said housings, a drawbar extending throughout the length of said car through said housings and having a collar adjacent each end, braces secured across said floor 70 on opposite sides thereof between said channels, and an additional pair of opposed braces secured across said floor and clamping said casing in position, substantially as set forth.

7. The combination in a mine car, of a floor, a housing adjacent each end of said floor and having flanges on its top and bottom forming a channel between the same, said housing being longitudinally divided, 80 a casing having one end nested in each of said housings, a drawbar extending throughout the length of said car through said housings and having a collar adjacent each end, braces secured across said 85 floor on opposite sides thereof between said channels, and an additional pair of opposed braces secured across said floor and clamping said casing in position said floor being extended beyond the ends of said drawbar 90 to form bumpers, substantially as set forth.

In witness whereof, I have hereunto set my hand and seal at Balkan, Kentucky this 5 day of June, A. D. nineteen hundred and twenty-five.

CHARLES F. CLAYTON. [L.S.]
